Attorney

UNITED STATES PATENT OFFICE.

OTTO J. KUHLKE, OF AKRON, OHIO.

RESILIENT BALL.

Application filed August 12, 1922. Serial No. 581,328.

To all whom it may concern:

Be it known that I, OTTO J. KUHLKE, a citizen of the United States, residing at Akron, in the county of Summit, State of Ohio, have invented certain new and useful Improvements in Resilient Balls, of which the following is a specification.

My invention relates to improvements in resilient balls for use in games wherein a striking implement is used and it has particular reference to balls adapted for use in the game of golf.

The particular purpose of the present invention is to provide a golf ball that is more active, or responsive, under a quick, hard blow than existing types of golf balls, and is also particularly adapted for accurate putting.

My invention is also directed toward providing a golf ball, which, in combination with the above enumerated characteristics, possesses sufficient symmetry, weight, and balance to enable it to maintain its direction while it is in flight.

Still another object of the present invention is to provide a golf ball which will function in the manner above set forth and which may be produced by the manufacturer at a relatively low cost.

Other objects, together with the advantages to be derived in the practice of my invention, will become apparent and the nature of the invention will be fully understood when the following detailed description is read in conjunction with the drawings accompanying and forming a part of this specification.

It is to be understood, however, that the present disclosure is merely illustrative of a preferred form of my invention and is not to be construed as limiting the scope or spirit of my invention unless such limitations are indicated in the claims appended hereto, nor is the invention limited to golf balls, but may be applied in other shapes or forms.

In the drawings:

Figure 1 is a side elevational view of a golf ball constructed in accordance with the principles of my invention, parts of the ball being broken away and shown in section;

Figure 2 is a view partly in section, and partly in elevation, illustrating certain component parts of my invention; and

Figure 3 is a sectional view of one of the elements of my invention.

The golf ball of my invention preferably comprises a core 1 that is constructed of fine steel wire wound in any suitable manner into the form of a hollow sphere. Preferably the sphere is formed from a continuous strand of wire wound in superposed convolutions so that a highly elastic or resilient body is formed, which will quickly rebound when struck, the air confined within the sphere acting as a cushion. The sphere or core 1 thus provided is impregnated with a suitable coating designed to tie the convolutions together, confine the air within the sphere, and to impart additional resiliency. In the present form of the invention a composition of rubber is preferred of a character suitable for impregnating the wire and forming a hollow, air-tight sphere that is possessed of resiliency, combined with sufficient rigidity to prevent its permanent deformation, and a degree of weight sufficient to enable the ball to maintain its direction in flight.

Around the sphere or core 1, a layer 2 of highly resilient rubber or rubber composition is utilized to act as a medium that provides for a quick rebound of the ball under the effect of a hard blow. Preferably the material of the layer 2 is compressed and maintained under compression in order to increase its inherent resiliency and to thereby provide a highly reactive element which will quickly respond and rebound from a golf club, replacing the usual wound rubber found in the present type of golf ball. In order to secure and maintain the proper degree of compression of the layer 2, it is provided, preferably, with apertures or cells 3 and is covered with a sheath 4. The apertures 3 may be arranged in the layer 2 in any desired manner, but in this instance are formed through the entire thickness of the layer and substantially radially thereof. The sheath 4 is formed of tightly wound thread or cord, such as linen, silk, or other material, wound so as to provide a layer of the desired thickness and flexibility around the layer 2. Around the layer 2, a resilient covering 5 is provided of gutta percha, balata, or other suitable material.

The foregoing structure provides for a golf ball that is highly active when struck

with a driving blow and yet may be accurately putted. It is well balanced and when properly constructed possesses the desired weight and balance. At the same time it may be manufactured at a relatively low cost.

The invention is not limited to the exact arrangement shown, nor to the proportions of the various layers as indicated in the drawings. I believe that I am the originator of a golf ball, or other playing ball, which is provided with a metallic member, such as the wound wire, rubber impregnated sphere, which is used to impart both weight and resilience to the ball. Prior golf balls have used a metallic core, but, so far as I am aware, none has ever been used in which the metallic core possessed a certain amount of resilience in and of itself. I am also the first to use a rubber element in the ball which is held under compression by a winding of core or thread, which holds the rubber under compression. I am, therefore, entitled to a broad range of equivalents in the construction of the appended claims.

What I claim is:

1. A golf ball comprising, a hollow wound wire sphere the convolutions thereof being impregnated with rubber, and an outer layer of rubber over the sphere.
2. A ball comprising, a wound wire sphere impregnated with rubber and enclosing an air chamber therein.
3. A ball comprising, a wound wire, hollow sphere, a cellular envelope over the sphere, and a winding of substantially inextensible cord over the envelope holding it under compression.
4. A ball comprising, a wound wire sphere said sphere being impregnated with rubber, a layer of rubber over the sphere said layer being under compression, and a winding of cord over the layer maintaining the compression therein.
5. A ball comprising, a wound wire sphere said sphere being impregnated with rubber, a cellular envelope of rubber over the sphere said layer being under compression, and a winding of cord over the envelope maintaining the compression therein.
6. A ball comprising, a metallic wire

sphere impregnated with rubber and having resilient properties and enclosing an air chamber.

7. A ball comprising, a wound wire, hollow sphere impregnated with rubber and enclosing an air chamber, a layer of rubber about said sphere, and means for maintaining the layer of rubber under compression. 55

8. A ball comprising, a wound wire, hollow sphere impregnated with rubber and enclosing an air chamber, a layer of rubber about the sphere, a substantially inextensible cord sheath over the rubber layer, and a cover. 60

9. A ball comprising, a wound wire, hollow sphere impregnated with rubber and enclosing an air chamber, a layer of rubber over the sphere said rubber being under compression, and a winding of cord over the said layer maintaining it under compression. 65

10. A ball having located within it a wound wire sphere, the interstices of which are filled with rubber and a cover over the sphere. 70

11. A ball comprising a metallic sphere composed of a plurality of layers of wire impregnated with rubber and confining an air chamber therein. 75

12. A ball comprising a hollow metallic sphere composed of a continuous strand of wire wound in superposed convolutions, said sphere being impregnated with rubber, the said sphere confining an air space therein. 80

13. A ball comprising a hollow air-tight sphere formed from a continuous strand of wire wound in superposed convolutions and impregnated with rubber, and a cellular envelope over the sphere. 85

14. A ball comprising a hollow sphere consisting of a strand of wire wound in superposed convolutions, a layer of rubber over the sphere, said layer being under compression, and a winding of cord over the layer maintaining the compression therein. 90

15. A golf ball comprising a wound wire, hollow sphere, the convolutions of which are impregnated with rubber, and an outer cover. 95

OTTO J. KUHLKE.
